UNITED STATES PATENT OFFICE.

JOHN H. BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

REPEATER SYSTEM.

1,257,303.

Specification of Letters Patent. Patented Feb. 26, 1918.

Application filed May 16, 1916. Serial No. 97,763.

To all whom it may concern:

Be it known that I, JOHN H. BELL, a subject of the King of Great Britain, residing at East Orange, in the county of Essex 5 and State of New Jersey, have invented certain new and useful Improvements in Repeater Systems, of which the following is a full, clear, concise, and exact description.

This invention relates to telegraph systems and more particularly to improvements in so-called repeater systems whereby, in association with two or more independent line circuit sections or signaling circuits, current action first taking place in one circuit section is automatically relayed into the other circuit sections, such repeating operations being reciprocal with respect to a plurality of line sections. The repeater system which comprises this invention is adapted for use 10 with telegraphic codes or arrangements wherein the signal units or current impulses are separated by no-current intervals.

The principal object of this invention is to simplify the arrangement of repeater circuits for a system of the above character, in order to permit the employment of devices of least complication of parts and to provide that each line section forming one of a dual or multiple circuit group may be identically equipped with respect to each other as 25 regards repeating devices, and to avoid the necessity of employing apparatus locally common to a group of repeating devices. The last mentioned feature permits of 30 greater flexibility in the interconnecting and grouping of circuits or sections for rendering service of this character, owing to the fact that the repeating equipment of one line section is typical of the equipment of 35 each one of the other line sections associated therewith.

In accordance with this invention, each signaling or main line section making up the telegraphic line or system is provided 45 with two polarized relays and one alternating or universal current relay, each directly responsive to the currents which traverse the associated main line circuit section. The switching contacts of the universal current 50 relay of one line section are arranged to control the operating circuits of the repeating relays common to the other line sections comprising a repeating group. Accordingly, when originating or controlling current 55 pulses, separated by no-current intervals, are

present in one line section, the relays of the other line sections are disabled, while the repeating relays of the primarily active section operate to include a suitable source of current at the repeating point to set up current changes and no-current intervals in the other sections, corresponding in character to the changes set up in the first section. This system is adapted to relay so called single current or double current signaling combinations, and may be employed for either operating printing telegraphs or for manual telegraph working.

In the accompanying drawing, Figure 1 illustrates diagrammatically a repeater 70 equipment in accordance with this invention, whereby the reciprocal relaying of signals may be effected from one to the other of two main line sections, and Fig. 2 similarly illustrates a multiple repeater equipment suitable for reciprocally relaying signals from 75 one section to the other section of a multiple line group formed of three line sections.

The features of this invention may be readily understood from a description of the 80 operation of the system. Referring first to Fig. 1, let it be assumed that the ends (not shown) of the main line conductors 1 and 2 terminate in different stations and that each terminal is equipped with apparatus 85 suitable for sending or receiving messages of this character.

In accordance with well-known telegraphic practice, telegraph printing systems may be operated by signaling impulses 90 formed of intermittent applications of current of the same polarity, also by current impulses of changing polarity, all of which may be applied to a main line section by the transmitter at a sending station thereon. 95 Such characteristic current impulses, in turn, being translated into a printed message at a receiving station, all in a manner well-known in the art. Assuming now that such impulses supplied from suitable sources 100 of grounded battery are present in the line circuit 1 at a distant station (not shown), it will be apparent these currents may complete circuit through the contacts 15 of a polarized relay 13, the coöperating contacts and armature of an alternating current relay 12, the winding of a second alternating current relay 5, the winding of a polarized relay 6, thence through the winding of a second polarized relay 7 to the earth connection. The relay 110

5 is responsive to each character of current action through the circuit traced and, being adapted to respond quickly when energized and to release slowly when deenergized, it 5 remains operated under the usual cessations of current present at certain instants in the spacing or changing of polarity with respect to the transmitted impulses; therefore, during the time a message is being transmitted 10 over the line 1, the contacts of this relay remain separated, thereby disconnecting the repeating group, comprising relays 12, 13 and 14. Although the relay 5 continues energized by the transmitted impulses, the 15 same current through the polarized relays 6 and 7 act selectively therein to suitably translate each impulse of current. The polarized relays are biased to render their respective normal contacts 8 and 10 closed in 20 unison with each cessation of current in the line 1 such as takes place in the spacing of impulses or between reversals in current direction. Accordingly, in response to intermittent impulses of positive current, the relay 6 will be operated to set up corresponding separations and closures, respectively, of its contacts 8 and 9 during which time no operating effect is, however, produced in the 25 other polarized relay 7, except to incidentally add some increase of pressure to the normal biasing force acting to close its contacts 10. Therefore, the relay 7 remains inert under positive impulses of current, while the relay 6 responds thereto in phase with 30 such impulses.

The relayed currents may be traced by assuming that, under the influence of a positive impulse of current over the main line section 1, the relay 7 remains inert while the 40 relay 6 is operated, thereby causing the separation of its contacts 8 and the closing of its contacts 9, whereby the positive pole of a grounded battery 19 is connected to the line conductor 2, and accordingly energizes this line in unison with the originating impulses in the line 1. Now, if immediately following the positive impulse or impulses, an impulse of negative current is received 45 from the main line conductor 1, the relay 6 is restored and remains inert, while the negatively poled relay 7 is operated to separate its contacts 10 and close its contacts 11, thereby connecting an oppositely poled grounded battery 20 to send a corresponding 50 negative impulse of current out over the line conductor 2.

The arrangement whereby the contacts 8 of the relay 6 are connected in parallel with the contacts 10 of the relay 7, and the corresponding relation of the contacts 17 of the relay 14 with respect to the contacts 15 of the relay 13, while not an essential feature of this system, is employed only for the reason that in practice it is expedient 65 that these relays be of uniform type, there-

fore connecting the normal contacts of the second polar relay in parallel with the corresponding contacts of the first polar relay merely serves to insure circuit over this contact path.

The operations by which signaling impulses are relayed from the line circuit 2 into the line circuit 1 are the same as those already described, except that the operations take place through similar action of other 70 relays. In tracing such a message, currents from the line 2 complete circuit through the contacts 8 of the polarized relay 6, the contact and armature of the relay 5, the winding of the alternating current relay 12, 80 thence to earth through the serially connected windings of the polarized relays 13 and 14. During the time current action is present in the line circuit 2, the relay 12 continues energized, thereby separating its 85 contacts to disconnect the repeating group comprising relays 5, 6 and 7. The polarized relays 13 and 14 now selectively respond to the impulses present in the line circuit 2, in the same manner as hereinbefore described 90 for the corresponding operations of the relays 6 and 7. The closing of the contacts 16 of the relay 13, in response to a positive impulse, connects the positive side of the grounded battery 19 to the line conductor 95 1. Accordingly, under an impulse of negative current in the line circuit 2, the relay 13 restores and remains inert, while the relay 14 is operated to close its contacts 18, thereby including the negative side of the 100 grounded battery 20 with the line conductor 1.

From the foregoing description, it will be readily understood that, during the time messages are being transmitted from the line 105 circuit 1, the group of relays designated as B are disabled, while the relays comprising the group A are active to repeat the message into the line 2, and conversely, when a message is transmitted from the line circuit 2, the repeating group A is disabled, while the group 2 is active to repeat the message into the line circuit 1, as described.

Referring to Fig. 2 of the drawing, the operation by which signaling impulses of 110 the same character as those already described in connection with Fig. 1 are repeated from one line circuit into the other line circuits, will now be described. Let it be assumed that initial current impulses are 115 present in a line circuit 21, as set up by a suitable transmitter at a distant station (not shown) on this line. The path of these currents may be traced through the cooperating contact 50 and armature of a universal current relay 47, the contact 38 and armature of a universal current relay 37, a conductor 32, the winding of a polarized relay 25, the winding of a second polarized relay 26, a conductor 33, thence to earth through the 120 125 130

winding of an alternating or universal current relay 27. The relay 27 is energized by these currents to continuously separate its contacts 28 and 30, and to close its contacts 5 29 and 31 during the passage of signal current impulses. The various circuit changes set up by the operation of the relay 27 are first, the separation of its contacts 28 disconnects the repeating group D comprising 10 relays 35, 36 and 37, all corresponding with the line 22; second, the separation of its contacts 30 disconnects the repeating group E comprising relays 45, 46 and 47, all corresponding with the line 23; third, the closing 15 of the contacts 29 connects the line circuit 22 to the common or bus conductor 34 of the relays 25 and 26; and fourth, the closing of the contacts 31 connects the line circuit 23 also to the bus conductor 34, thereby establishing a physical connection between the 20 line circuits 22 and 23. Now, at the instant a positive impulse of current is received over the line circuit 21, the polarized relay 25 remains inert, while the associated polarized 25 relay 26 is operated to close its contacts, thereby including the positive pole of the grounded battery 19 with the bus conductor 34, thence this current branches into the main line circuits 22 and 23. The path 30 of the repeated impulse for the line 22 may be traced from the bus conductor 34 over the contacts 29 of the relay 27, a conductor 42, and the contacts 48 of the relay 47, while the corresponding impulse of current from 35 the bus conductor 34 reaches the line 23 over the contacts 31 of the relay 27. At the instant an initial impulse of negative current is transmitted over the line circuit 21, the polarized relay 26 is restored to remain 40 inert, while the polarized relay 25 is operated to close its contacts, thereby including the negative pole of the grounded battery 20 with the bus conductor 34, from which point this repeated current reaches the main 45 line circuits 22 and 23 over the respective paths already traced for the positive impulse of current from the battery 19.

The foregoing description of the operations taking place when a message is repeated from the line 21 to the lines 22 and 50 23 is typical of the action taking place when a message is repeated from either one of the latter line circuits to the other two lines. Accordingly in repeating signals 55 from the line 22 to the lines 21 and 23, the repeating group D is active, while the repeating groups C and E are respectively disconnected by the separation of the contacts 38 and 40 of the alternating current relay 60 37. The current impulses set up in the line circuit 22 may be traced therefrom by way of the contacts 48 of the relay 47, a conductor 42, the contacts 28 of the relay 27, a conductor 52, the serially connected windings of the polarized relays 35 and 36, a

conductor 44, thence through the winding of the alternating current relay 37 to the earth connection. In response to this current action in the line 22, the polar relays 35 and 36 selectively connect the associated batteries by way of the bus conductor 54 to the line circuit 21 over the contacts 39 of the relay 37, and the contacts 50 of the relay 47, and to the line circuit 23 by way of the contacts 41 of the relay 37 and the contacts 30 75 of the relay 27.

Messages originating in the line circuit 23 in a similar manner operate the repeating group E, comprising relays 45, 46 and 47, to first disable the repeating groups C and 80 D and, secondly, to cause the polarized relays 45 and 46 to connect the associated batteries to set up repeated impulses of current in the lines 21 and 22, all by way of contacts and conductors corresponding with those 85 already traced.

From the foregoing description, it will be apparent that with the present system, the repeating equipment of one line circuit is typical and a counterpart of the equipment of each one of the other line circuits associated therewith to form a repeating group.

Although several batteries have, for convenience, been shown in the drawing, it will 95 be understood that each set of correspondingly poled batteries may be, and preferably is, one and the same battery.

What is claimed is:

1. In a telegraph repeating system, a plurality of telegraph line circuits, sources of current, a plurality of line relays for each line circuit for repeating telegraphic signals from any one of said line circuits into the other ones of said line circuits, and contacts on said relays effective in said repeating operations to translate telegraphic intervals corresponding with predetermined periods of no current.

2. In a telegraph repeating system, a plurality of current sources, a plurality of telegraph line circuits, a universal current line relay and a first and second polarized line relay for each one of said line circuits, contacts operated by the universal current relay 100 105 of any line circuit for disabling the line relays of the other line circuits and for joining the other line circuits one with another, and contacts operated by the polarized relays of any line circuit for repeating 110 115 telegraphic signals corresponding with predetermined periods of positive current, of negative current and cessation of current into the other ones of said line circuits.

3. In a telegraph repeating system, a plurality of telegraph line circuits, a repeating device normally connected to each line circuit, and adapted to receive signals over the line to which it is connected, a source of current, means controlled by each repeating 125 130

device for disconnecting another repeating device from its line and for intermittently connecting the source of current to the other line circuits in response to the signals received over the line circuit to which it is connected.

4. In a telegraph repeating system, a plurality of telegraph line circuits, a repeating device normally connected to each line circuit comprising a plurality of relays, adapted to receive signals over the line to which they are connected, a source of current, means controlled by each repeating device for disconnecting another repeating device from its line and for intermittently connecting the source of current to the other line circuits in response to the signals received over the circuit to which it is connected.

5. In a telegraph repeating system, a plurality of telegraph line circuits, a repeating device normally connected to each line circuit, comprising a plurality of polarized relays and a universal current relay, said relays being adapted to receive signals from the line circuit to which they are connected, a source of current, means controlled by the universal current relay for disconnecting another repeating device from its line throughout the receipt of a series of signals over the line to which it is connected, and means controlled by the polarized relays for intermittently connecting the source of current to the other line circuits in response to said signals.

In witness whereof, I hereunto subscribe my name this 12th day of May, A. D. 1916.

JOHN H. BELL.
